UNITED STATES PATENT OFFICE.

ALBERT H. HARDMAN, OF WHEELING, WEST VIRGINIA.

SWITCH.

Original application filed August 26, 1926, Serial No. 131,718. Divided and this application filed April 1, 1927. Serial No. 180,244.

The present invention is directed to improvements in switches and is a division of my copending application for signals for automobiles, filed August 26, 1926, Serial No. 5 131,718.

The primary object of this invention is to provide a novel construction of switch actuated through the movement of the service brake pedal to effect closing of the circuit 10 through the light bulb which is to illuminate the stop signal casing.

In the accompanying drawing:

Figure 1 is a sectional view through a portion 15 of an automobile showing the switch in place thereon.

Figure 2 is a longitudinal sectional view through the switch.

Figure 3 is a sectional view on line 3—3 of Figure 2.

20 The switch is constructed in such manner that a light bulb will be illuminated from actuation of the brake pedal in order to display a stop signal carried by a casing 1 mounted upon the rear of the automobile.

25 The switch is mounted at any convenient point, as for example, beneath the floor boards and service brake pedal 1, the floor boards being indicated by the numeral 3.

The switch comprises a casing 4 having a 30 base flange 5 at its open side, and a closure plate 6 disposed against said side of the casing and against said flange and has flanges 7 which are overturned about the margins of the flange 5. The casing and closure are made

35 of sheet metal and by bending back any one of the flanges 7 the closure may be slid out of engagement with the flange so as to permit access to the interior of the casing. At its side opposite its open side the casing is 40 formed with an opening 8, and plates 9 and 10 of insulating material are arranged respectively against the inner and outer sides of this wall of the casing.

A threaded contact post 11 is fitted through 45 openings in the said insulating plates 9 and 10 and is provided at its ends within the casing with a head 12 and has threaded onto it nuts 13, one of which is to be tightened to bear against the plates 10, the head 12 en- 50 gaging the other plate so as to anchor said post, and, at the same time, connect the plates 9 and 10 and clamp them to the wall of the casing at the corresponding end of the opening 8, the other nut being adapted to be tightened to bind the post to a conductor

wire. A binding post 13 is fitted through openings in the insulating plates 9 and 10 and has nuts 14 threaded thereon to secure the same in place and draw the said plates together at their other ends, as well as to an- 60

chor another conductor wire, and this binding post serves also to anchor one end of a leaf spring contact 15 which extends from the post at an angle to the plate 9 and with its free end positioned opposite and normally 65

out of contact with the head 12 of the contact post 11. The numeral 16 indicates a stem which is slidably fitted through openings 17 in the opposite end walls of the casing and a rectangular head 18 of insulating material 70

is fixed upon the stem between the collars 19 secured thereon, and a spring 20 is arranged upon the stem and bears at one end against one end wall of the casing and at its other 75

end against said head. The end of the stem which extends through the last mentioned end wall of the casing is provided with an eye 21, and a spring 22 is connected at one end to 80

said eye and at its other end to a rod 23 which leads to a clamp 24 secured upon the 85

rod 25 which leads from the service brake pedal 2 to the service brake for the rear 90

wheels of the vehicle. The head 18 is normally located substantially out of contact with the leaf spring contact 15 but, it will 95

be evident by reference to Figure 2, that when a pull is exerted upon the stem 16 toward the left in said figure, and which pull will be exerted when the service brake pedal is actuated to apply the brake, the head 18 will ride against the contact 15 and cause the same to contact with the head 12 of the post 11, thus closing the circuit in which this post and the binding post 13 are located, and will thereby illuminate the bulb in the stop cas- 100

ing 1.

The binding posts 11 and 13 are in circuit with the battery 26 and stop signal casing 1 through the conducting wires 27 and 28 in order that when the service brake pedal 2 is actuated the circuit will be closed to illuminate the bulb in said casing.

Having thus described the invention, I claim:

A mechanically operated switch comprising 105 a casing, a stem slidably mounted therein and having an eye upon its forward end for the connection of the mechanical operating means, a head of insulating material carried by the stem, the casing having an open side, 110

a plate of insulating material at said side of the casing, spaced binding posts upon said plate for the connection of conductor wires, a resilient leaf contact secured at one end by 5 one of said posts and having its other end deflected and located opposite the other post and normally spaced therefrom and located in the path of movement of said head, and a spring upon the stem engaging at one end

against one end of the casing and at its other 10 end against the head and normally holding the stem in inactive position with relation to said leaf contact, said eye when engaged with an end wall of the casing serving to limit the rearward movement of the stem. 15

In testimony whereof I affix my signature.

ALBERT H. HARDMAN. [L. s.]
